Primary Examiner—Susan J. Lucas

[57] CLAIM

The ornamental design for a corner connector for ceiling lighting fixtures, as shown and described.

DESCRIPTION

FIG. 1 is a bottom, front perspective view of a corner connector for ceiling lighting fixtures showing my new design, two lighting fixtures being fragmentarily shown in broken lines for illustrative purposes only;

FIG. 2 is a top plan view thereof;

FIG. 3 is an end elevational view thereof on an enlarged scale, the opposite end being a mirror image;

FIG. 4 is a top, rear perspective view thereof on a reduced scale;

FIG. 5 is a top, front perspective view thereof;

FIG. 6 is a top, front perspective view of a second embodiment of my new design;

FIG. 7 is a top, front perspective view of a third embodiment of my new design;

FIG. 8 is a top, front perspective view of a fourth embodiment of my new design;

FIG. 9 is a top, front perspective view of a fifth embodiment of my new design;

FIG. 10 is a top, front perspective view of a sixth embodiment of my new design;

The embodiments of the corner connector differ only in the number of adapters.
